UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

CONVERTIBLE BOX-CAR.

1,386,765.

Specification of Letters Patent. Patented Aug. 9, 1921.

Application filed December 2, 1920. Serial No. 427,744.

To all whom it may concern:

Be it known that I, ARGYLE CAMPBELL, a citizen of the United States, residing at Chicago, in the county of Cook and State 5 of Illinois, have invented a certain new and useful Improvement in Convertible Box-Cars, of which the following is a full, clear, concise, and exact description, reference being had to the accompanying drawings, 10 forming a part of this specification.

This invention relates to improvements in convertible box cars.

In the operation of railroads, there is a constantly increasing demand for more continuous use of all rolling stock and particularly in connection with box cars. At certain seasons of the year, especially in the case of the so-called grain-carrying roads, there is a heavy demand for box cars for the 20 transportation of grains and in the intervening periods, the demand for said cars on those roads is appreciably less and large numbers of the box cars are frequently employed in other sections of the country in 25 the carrying of packaged loads or other loads which are not of a "fluid" nature. It is highly desirable that all box cars be interchangeably adapted for the carrying of either packaged loads or loads of a fluid 30 character such as grain in order to maintain such box cars constantly in productive operation. An essential characteristic of 35 of such a convertible car is that, when it is not being employed for the carrying of grain, no capacity shall be lost or interference permitted with the loading or unloading of the packages, boxes or the like. Another essential characteristic of a successful convertible box car of the type indicated is that the means employed to convert 40 the car shall not be of excessive weight or excessive in cost of manufacture or application.

The object of my invention is to provide 45 a convertible box car having a simple, efficient and economical arrangement whereby the car is adapted for use either as an ordinary box car to carry so-called packaged loads without loss of carrying capacity or 50 as a car to carry bulk loads such as grain, coal, or like commodities wherein sufficient of the load may be easily discharged to relieve the pressure behind the necessary inside door to permit opening of the latter.

55 Other objects of the invention will more

clearly appear from the description herein-after following, considered in connection with the drawing and the appended claims.

In the drawings forming a part of this specification, Figure 1 is a vertical, sectional view taken through the usual side door opening of a car showing my improvements in connection therewith. The section extends from the side of the car to the center line thereof only, it being understood that the 60 arrangement will preferably be duplicated on both sides of the center sill construction. Fig. 2 is a vertical, sectional view corresponding substantially to the line 2—2 of Fig. 1, parts being broken away in order to accommodate 65 the showing of certain parts of the construction. Fig. 3 is a detail, horizontal, sectional view corresponding substantially to the line 3—3 of Fig. 2. Fig. 4 is a view similar to Fig. 1 illustrating another embodiment of 70 the invention. And Fig. 5 is a view similar to Fig. 2 corresponding to the section line 5—5 of Fig. 4. Parts are broken away in Fig. 5 to better accommodate the view on the sheet.

Referring first to the construction illustrated in Figs. 1, 2 and 3, 10 indicates a channel side sill of the car, 11 one of the channel center sills, and 12—12 two of the needle beams in the form of pressings, the 85 needle beams illustrated being those commonly found in line with the side door posts. The usual side door opening of the car is defined by the threshold 13 and side posts 14—14, the lintel not being shown as 90 the same is unnecessary for the understanding of the invention. The greater portion of the floor of the car is permanent or fixed as indicated at 15, portions of said permanent floor being omitted opposite the side 95 door openings for a width slightly greater than the width of the door opening and for a depth extending from the threshold 13 to the point 115 preferably about half way to the center sill 11.

The omitted portion of the permanent floor above referred to is replaced by a floor door 16 pivoted along its outer edge adjacent the threshold 13 as indicated at 17, it being understood that said floor door 16, 105 when in horizontal position, will complete the flooring of the car and will lie flush with the fixed portion of the flooring. The floor door 16 is adapted to be supported along its edges on top of the needle beams 12 as 110

indicated in Fig. 2 and at its inner edge is adapted to be supported on an intermediate sill section 18 extending between the needle beams 12. As will be understood by those skilled in the art, the floor door 16 is adapted to assume a vertical position as indicated by the dotted lines 16^a in Fig. 1 in which position it extends across the door opening and is adapted to partially close the latter to a height corresponding to the width of the door from its hinged point to the free edge thereof. Said floor door 16 is adapted to be retained in its upright or vertical position by any suitable means such as the latches 19—19.

Due to the variations in the weights of different grains, grain cars are filled to different levels dependent upon the particular grain forming the load. When the car is employed for carrying certain other bulk commodities, as for instance, coke, the car may be filled to a still higher level without unduly weighting the car. In box cars of the usual standards, a floor door extending from the threshold to the point 115, as illustrated in the drawing, is not of sufficient length when in a vertical position across the side door opening to retain the usual grain loads and it is therefore necessary to extend the height of the door when positioned across the side door opening of the car. To accomplish this result, I employ door extension boards as indicated at 20—20. Said extension boards 20—20 are stored within a discharge hopper 21 extending between and secured to the needle beams 12—12. The boards 20, when within the hopper 21, are supported on suitable cleats 22—22 at each end of the hopper, said cleats being notched as indicated at 23—23 to fit the lower edges of the boards. Additional cleats 24—24 are secured to the needle beams, said cleats 24 having guide slots 25 therein to accommodate the boards as clearly indicated in Fig. 1.

45 The lower end of the hopper 21 is closed by a door 26 pivoted to the chute proper as indicated at 27, said door 26 forming a grain seal with the chute as indicated at 28. The door is held and locked in closed position by any suitable means such as the sliding bolt 29, said bolt 29, when in locked position, preferably having a perforation 30 alined with a corresponding perforation 31 carried by the hopper so as to accommodate the usual lead seal.

When the boards 20 are employed to extend the height of the floor door, said boards may be held in place on top of the edge of the floor door in suitable guides formed by 60 vertically extending Z-bars 32—32 secured to the inner sides of the door posts as indicated in Figs. 2 and 3, it being understood that the door extension boards are inserted vertically in the guides just described.

65 In the particular instance shown in Figs.

1 to 3, the discharge hopper 21, which is located closely adjacent the threshold 13, is relatively narrow in order to minimize the amount and weight of the material required to form the same. As will be understood by those skilled in the art, the door extension boards 20 are made of a length slightly less than the distance between the two needle beams 12 but of a somewhat greater length than the distance between the door posts. 75

From the preceding description, it will be seen that my improved car is adapted for use as an ordinary box car when the boards 20 are stored within the hopper 21 and the floor door 16 is in horizontal position. In this condition of the car, it is evident that no load-carrying space of the car is lost and none of the parts employed in converting the car from one type to another is subject to any possible injury from the load carried by 80 the car. When my improved car is converted to use as a grain-carrying car, I am enabled to obtain the necessary height for the inner grain door and at the same time provide a discharge hopper by which a portion of the 85 grain or other bulk load may readily be discharged from behind the grain door in order to permit the latter being readily opened and access obtained to the remaining portion 90 of the load. 95

In actual practice, a flexible connection, not shown, may be employed to attach the extension boards 20 to the car so as to prevent their being accidentally thrown away or displaced. Furthermore, said extension 100 boards may be inscribed with suitable legends to indicate the railroad and the particular car to which the boards belong.

Referring next to the construction illustrated in Figs. 4 and 5, the general arrangement of car underframe, permanent flooring and side door opening is the same as illustrated in Figs. 1 to 3. In the arrangement shown in Figs. 4 and 5, however, I employ a considerably larger hopper, the bottom of 105 which is defined by a downwardly and outwardly sloping hopper sheet 40, the outer side thereof by the channel side sill 110 and the ends in part by the pressed needle beams 112 and depending triangular hopper sheets 115 41—41 secured to the bottoms of the needle beams. A larger door 126 is also used, the same having a grain seal with the portions of the hopper defining the discharge opening as indicated at 128. Said door 126 may be held in closed position by a sliding bolt arrangement as indicated at 129.

As in the case of the construction illustrated in Figs. 1 to 3 so in the construction illustrated in Figs. 4 and 5, I provide a pivoted floor door 116 arranged in the same manner as the door 16 but extending to the center sill. It will be obvious that the door 116 is adapted to form either a portion of the flooring of the car or a partial closure 125 130

for the side door opening. Instead, however, of employing door extension boards in the form of the detached boards 20, I employ one or more door extension boards 120—120 preferably united by suitable straps 42, the same forming in effect a relatively narrow door. Said door extension boards 120 are pivotally attached to the floor door 116 as indicated at 43, the pivotal connection being effected by 10 means of slidable hinge straps 44 mounted within brackets 45 secured to the under side of the floor door 116. Said hinge straps 44 are provided at their ends with enlarged heads 46 to prevent the same being pulled 15 out from the brackets 45.

The door extension boards 120 are also made of a length slightly less than the distance between the ends of the hopper but of somewhat greater length than the distance 20 between the door posts. It is obvious that said boards 120 are adapted to lie within the hopper when the floor door 116 is in its horizontal position as shown in Fig. 4. The sliding hinge connection between said boards 25 and the door 116 is provided in order to permit the boards 120 being shifted relatively to the door 116 sufficiently to permit the latter to be properly supported, as indicated at 47, on the center sill construction. When the 30 floor door 116 is moved to its vertical position across the door opening, it is evident that the effective height thereof can be increased by swinging the extension boards 120 vertically and resting the same on the top 35 edge of the door 116. The door 116 and the extension boards 120 are adapted to be releasably retained in vertical position by any suitable means such as the latches 119—119.

The convertible car illustrated in Figs. 4 40 and 5 obviously possesses the same advantages as the type of car illustrated in Figs. 1 to 3 but possesses an advantage over the latter in one respect in that, on account of the larger hopper employed, it is better 45 adapted for the carrying of bulk loads such as coal and coke which do not flow as readily as grain.

I have herein shown and described what 50 I now consider the preferred manner of carrying out my invention but the same is merely illustrative and I contemplate all changes and modifications that come within the scope of the claims appended hereto.

I claim:

55 1. In a convertible box car, the combination with the car body having a side door opening, fixed flooring and an underframe; of a floor door located opposite said side door opening and pivotally mounted along 60 its outer edge and adapted to assume either a horizontal position as part of the car floor or a vertical position partially covering the door opening; a discharge hopper located opposite said side door opening and adapted to be covered by said floor door

when the latter is in horizontal position; and additional door extension means, positioned within said hopper when said floor door is used as a part of the car flooring, said means being adapted for positioning 70 across said door opening on top of the floor door when the latter is in its vertical position across said door opening.

2. In a convertible box car, the combination with the car body having a side door opening, fixed flooring and an underframe; of a floor door located opposite said side door opening and pivotally mounted along its outer edge and adapted to assume either a horizontal position as part of the car floor 80 or a vertical position to partially cover the door opening; a discharge hopper located opposite said side door opening and adapted to be covered by said floor door when the latter is in horizontal position; and a door 85 extension board, adapted for positioning across said door opening on top of the floor door when the latter is in its vertical position across said side door opening, said door extension board being of lesser length than 90 said hopper and adapted to be positioned lengthwise therein when said floor door is in horizontal position forming part of the floor.

3. In a convertible box car, the combination with the car body having a side door opening, fixed flooring and an underframe; of a floor door located opposite said side door opening and pivotally mounted along its outer edge and adapted to assume either 100 a horizontal position as part of the car floor or a vertical position to partially cover the door opening; a discharge hopper located opposite said side door opening and adapted to be covered by said floor door when the 105 latter is in horizontal position; additional door extension means, positioned within said hopper when said floor door is used as a part of the car flooring, said means being adapted for positioning across said door 110 opening on top of the floor door when the latter is in its vertical position across said door opening; releasable means for detachably holding said floor door in vertical position across the side door opening; and 115 means for holding said door extension means in said vertical position.

4. In a convertible box car, the combination with the car body having a side door opening and fixed flooring, the latter having 120 an opening therein opposite said side door opening; of a car underframe including a pair of needle beams spaced lengthwise of the car and each located approximately opposite a door post; a discharge hopper extending lengthwise of the car between said needle beams, said hopper having a hopper door at the bottom thereof and means for holding said hopper door in closed position; a floor door pivotally mounted at its outer edge ad- 130

ja⁵cent the threshold of said side door opening and adapted, in horizontal position, to occupy said opening in the flooring of the car and to cover the top of the hopper, said door being adapted to be positioned in a vertical position across said side door opening; and a door extension board, adapted to be positioned across said side door opening on top of said floor door when the latter is in 10 said vertical position, said door extension board being adapted to be positioned length-

wise within said hopper beneath the floor door when the latter is in said horizontal position.

In witness that I claim the foregoing I 15 have hereunto subscribed my name this 6th day of Nov. 1920.

ARGYLE CAMPBELL.
